UNITED STATES PATENT OFFICE.

HILLIARY ELDRIDGE, OF JERSEY CITY, NEW JERSEY, ASSIGNOR TO "SECRETARY," OF NEW YORK, N. Y., A CORPORATION OF NEW YORK.

GAS-STOVE.

SPECIFICATION forming part of Letters Patent No. 733,707, dated July 14, 1903.

Application filed March 18, 1903. Serial No. 148,370. (No model.)

To all whom it may concern:

Be it known that I, HILLIARY ELDRIDGE, a citizen of the United States, residing at Jersey City, in the county of Hudson and State 5 of New Jersey, have invented certain new and useful Improvements in Gas-Stoves, of which the following is a specification.

This invention relates to improvements in gas-stoves of the kind that are especially designed to be attached to the ordinary gas-burners for heating purposes.

The object of the invention is to produce a gas-stove that will have the greatest possible area of heat-radiating surface consistent with 15 the least consumption of gas. This is accomplished by constructing the heating parts of the stove in cylindrical form—that is, providing an inner cylinder of some fireproof material—for instance, metal, magnesia, clay, 20 or the like—and surrounding the said cylinder with a larger cylinder of foraminous material, preferably an asbestos fabric that can be heated to the proper condition.

By the above-described arrangement a combustion-chamber is formed between the inner and outer cylinders, and the gases are admitted to this chamber through a Bunsen burner covered by any suitable screen and provided with gas-outlets interjacent to the two cylinders. 30 The burning gases in this chamber will rise and completely envelop the inner cylinder and be reflected against the foraminous outer cylinder, from which the heat is effectually radiated.

If deemed advisable, the stove can be enclosed in any suitable manner—such, for instance, as by a perforated metal shield or a suitable frame provided with transparent sections of mica or the like.

The invention consists in the peculiar construction and arrangement of parts for producing the desired results, all as hereinafter fully described, and more particularly pointed out in the claims.

In the accompanying drawings, Figure 1 is a central vertical section of the stove and its supporting-base. Fig. 2 is a horizontal section on the line A A, Fig. 1. Fig. 3 is a plan view of the cap covering the combustion-chamber. Fig. 4 is a central vertical section

of the stove, showing a modified form of construction.

1 is a hollow support or base, of any suitable material, into which passes a gas-supply pipe 2, said pipe having an upwardly-projecting portion 3 centrally located in said base or support. Connected to the supply-pipe 3 is a Bunsen burner 4, provided with suitable lateral air-inlets 5. The base or support 1 has a conical recess therein in which the Bunsen burner is located, air being admitted to said burner, as shown by arrows in Fig. 1. Suitably secured to the Bunsen burner and forming part thereof is a flanged base-block 6, which is adapted to support the stove proper 65 and all its parts. In the lower portion of this block, or that part which engages the Bunsen burner, is a chamber wherein the gases are mixed and from which they flow through openings 9 into a thimble-shaped screen 8, of 70 any suitable material. Projecting upwardly from the block 6 is an annular flange 10, which engages the screen 8 and holds it in proper position, where it is supported by the reduced upwardly-projecting central portion 11 75 of the block 6, said screen being pierced to receive therethrough a tie-rod 12, which is tapped or otherwise suitably secured in the central portion 11. Supported on the top of the screen 8 and the upwardly-projecting portion 11 of the base-block 6 is a cylindrical shell 80 14, constructed of any suitable material—for instance, metal with a polished exterior surface or fire-clay or magnesia with a glazed surface. By polishing or glazing the surface 85 of the cylinder, the heat will be reflected against the inner wall of the surrounding foraminous cylinder 20 and tend to effectually increase heat radiation. When this heat-reflecting cylinder is constructed of metal, 90 it is usually made in the form shown in Fig. 1—that is, tubing is employed and caps 14 placed on each end thereof to prevent the ignited gases from entering said cylinder.

Surrounding the cylinder 14 is a cylinder 95 20, of foraminous material, that is suspended in the desired position by suitable nuts 21 22, engaging the tie-rod 12, the lower end of the foraminous cylinder being held in position by an upwardly-projecting circumferential 100

rib 16 on the block 6. The nut 21 engages the upper threaded end of the tie-rod 12 and is provided with a flange 21', upon which rests the inturned end 20' of the foraminous cylinder. The nut 22 is also adapted to engage the upper threaded end of the tie-rod 12 and has a flange 22', similar to that of the nut 21, the under part of said flange engaging the inturned portion 20' of the foraminous cylinder. Thus it will be seen that when the foraminous cylinder 20 is placed in position over the circumferential rib 16 and the inturned portion 20' rests on the flange of nut 21 the nut 22 can be adjusted on the tie-rod 12 and turned down until its flange 22' grips the inturned portion 20' of the cylinder and securely binds said portion between the flanges of the two nuts, thereby securing the foraminous cylinder in the proper suspended position. The nut 21 is provided with openings 21^a, forming a flue to permit the products of combustion to escape through the top of the stove. The nut 22 has openings 22^a for the same purpose as those explained for the nut 21. A binding-nut 25 engages the tie-rod 12 and securely retains the flanged nuts 21 and 22 in adjusted position.

A vertical combustion-chamber 26 is formed between the inner imperforate cylinder and the foraminous cylinder, into which flow the gases through the openings 9, leading from the mixing-chamber 7 into the screen 8. The screen 8 is thimble-shaped and covers the circular opening 28, through which the gases pass from the burner into the combustion-chamber. The burning gases in the combustion-chamber will impinge the inner wall of the foraminous cylinder, as shown by the arrows in Fig. 1, and be deflected directly up the combustion-chamber between the two cylinders, the inner cylinder constantly tending to reflect the heat against the foraminous cylinder, so that the said foraminous cylinder will be heated equally from bottom to top, thereby causing uniform heat radiation.

Surrounding the stove proper is a casing or shield 30, that can be constructed of any suitable material and in any desired manner or form, but herein shown cylindrical and having perforations 31, through which the condition of the stove proper may be remarked. This shield is not essential to the construction of the stove and is not employed to increase or diminish the heating qualities thereof, it being used to prevent accidental contact with the heated foraminous cylinder. The top of the shield or casing is covered with a cap or hood 32, which may be constructed in any suitable design or formation and is open at the top in the manner shown at 33 for the purpose of allowing the products of combustion to escape after being emitted from the combustion-chamber.

A modified form of the stove is shown in Fig. 4, wherein the central portion 11 of the block 6 is omitted, as is also the tie-rod 12 and the heat-reflecting cylinder 14. The ar-

angement of the Bunsen burner, the mixing-chamber in the block 6, and the thimble-shaped screen 8 is the same as shown in Fig. 1. The removal of the heat-reflecting cylinder will allow the burning gases to escape into the combustion-chamber with more freedom and heat the foraminous cylinder to the desired intensity. The cylinder 20 is supported in its proper position by having its inturned flanges 20' on the upper end of said cylinder engaged underneath by a flanged cap 35. Supported on the top of the shield or casing 30 is a plate 36, that has an annular recess 37, into which fits the flanged cap 35 in such manner that the inturned flanges 20' of the cylinder will be engaged and supported by the said cap 35 and plate 36. The flanged cap 35 and the plate 36 are held together by means of a bolt 38, that passes centrally therethrough and is engaged by a nut 39, the flanged cap 35 and the supporting-plate 36 having openings 35' and 36' therein, through which the products of combustion escape from the combustion-chamber.

Of course it is obvious that changes in the details of construction and practical application can be made without in any manner departing from the spirit of the invention. For example, while I have shown and described and particularly claimed the cylindrical form as having particular advantages other similar forms are advantageous also on grounds of beauty or for the purpose of producing a variety of designs.

Having thus described my invention, the following is what I claim as new therein and desire to secure by Letters Patent:

1. In a stove, the combination of a Bunsen burner, a base-block supported thereon, a heat-reflecting cylinder located above the base-block, a foraminous cylinder surrounding the heat-reflecting cylinder and forming a combustion-chamber between said cylinders, and a screen attached to the base-block under the heat-reflecting cylinder in such manner as to form an annular ingress for the gases from the Bunsen burner.

2. In a stove, the combination of a Bunsen burner, a base-block supported thereon, a heat-reflecting cylinder supported on said base-block, a foraminous cylinder surrounding the heat-reflecting cylinder and forming a combustion-chamber between said cylinders, a screen attached to the base-block under the heat-reflecting cylinder in such manner as to form an annular ingress to the combustion-chamber for the gases from the Bunsen burner, and a shield surrounding the foraminous cylinder and supported on the base-block, for the purposes described.

3. In a stove, the combination of a Bunsen burner, a base-block supported thereon, a screen seated in an annular recess in the base-block, a heat-reflecting cylinder located above the screen, a foraminous cylinder surrounding the heat-reflecting cylinder and forming a combustion-chamber between the

cylinders, a vertical tie-rod secured in the base-block, and means engaging said rod to support the cylinders in proper position and with proper relation to each other, for the purpose explained.

4. In a stove, the combination of a Bunsen burner, a base-block supported thereon, a cylinder of foraminous material supported on said block, a heat-reflecting cylinder within said foraminous cylinder, a rod attached to the block, apertured nuts engaging the rod and foraminous cylinder, and a screen under the heat-reflecting cylinder covering the gas-inlet to the foraminous cylinder.

5. In a stove, the combination of a Bunsen burner, a base-block supported thereon, a rod attached to the block, a flanged nut on the rod, a foraminous cylinder having an in-

turned edge engaging the flanged nut, and a flanged clamping-nut on the rod adapted to engage the inturned edge of the foraminous cylinder and suspend said cylinder in proper position on the base-block.

6. In a stove, the combination of a Bunsen burner, a base-block supported thereon, a screen secured in a recess on top of the base-block, a heat-reflecting cylinder supported above said screen, a foraminous cylinder surrounding said heat-reflecting cylinder, and means for supporting said cylinder so as to form a combustion-chamber for the gases.

HILLIARY ELDRIDGE.
